CLAIM

The ornamental design for an airgun stock, as shown and described.

DESCRIPTION

FIG. 1 is a back, top, right side perspective view of an airgun stock showing my new design.

FIG. 2 is a front elevation view.

FIG. 3 is a back elevation view.

FIG. 4 is a top view.

FIG. 5 is a bottom view.

FIG. 6 is a right side elevation view; and,

FIG. 7 is a left side elevation view.

The broken lines in the drawings are used to illustrate unclaimed parts of the invention and form no part of the claimed design.

1 Claim, 7 Drawing Sheets
